US00D869578S

(12) **United States Design Patent** (10) **Patent No.:** **US D869,578 S**
(45) **Date of Patent:** **** Dec. 10, 2019**

(54) **EXERCISE BELT**

(71) Applicant: **Shock Doctor, Inc.**, Fountain Valley, CA (US)

(72) Inventors: **Katherine Voigt**, Millersville, MD (US); **James Creath Frazier**, Hinesburg, VT (US)

(73) Assignee: **Shock Doctor, Inc.**, Fountain Valley, CA (US)

(**) Term: **15 Years**

(21) Appl. No.: **29/625,956**

(22) Filed: **Nov. 14, 2017**

(51) **LOC (12) Cl.** **21-02**

(52) **U.S. Cl.**

USPC **D21/662**

(58) **Field of Classification Search**

USPC 119/856, 857; 128/876; 482/14, 91, 482/148; 602/1, 6, 19; D2/624, 625, D2/627; D21/662, 683, 694, 798; D29/100, 101.1–101.5; D30/144, 152; D24/190; D6/608

CPC A61F 5/028; A61F 13/148; A61F 5/03

(57) **CLAIM**

The ornamental design for an exercise belt, as shown and described.

DESCRIPTION

FIG. 1 is a front perspective view of exercise belt illustrating a first embodiment of our new design;

FIG. 2 is a front view of the embodiment of FIG. 1;

FIG. 3 is a back view of the embodiment of FIG. 1;

FIG. 4 is a left side view of the embodiment of FIG. 1;

FIG. 5 is a right side view of the embodiment of FIG. 1;

FIG. 6 is a top view of the embodiment of FIG. 1;

FIG. 7 is a bottom view of the embodiment of FIG. 1;

FIG. 8 is a front perspective view of exercise belt illustrating a second embodiment of our new design;

FIG. 9 is a front view of the embodiment of FIG. 8;

FIG. 10 is a back view of the embodiment of FIG. 8;

FIG. 11 is a left side view of the embodiment of FIG. 8;

FIG. 12 is a right side view of the embodiment of FIG. 8;

FIG. 13 is a top view of the embodiment of FIG. 8; and,

FIG. 14 is a bottom view of the embodiment of FIG. 8. The broken lines shown in the drawings are for the purpose of illustrating portions of the exercise belt, which form no part of the claimed design. The dash-dot-dash lines shown in FIGS. 8, 13 and 14 are directed to boundary lines, which form no part of the claimed design.

1 Claim, 14 Drawing Sheets
